CLAIM

The ornamental design for skin hook as shown and described.

DESCRIPTION

FIG. 1 is a perspective view of a skin hook showing my new design.

FIG. 2 is a first side elevation view of the skin hook of FIG. 1.

FIG. 3 is a second side elevation view of the skin hook of FIG. 1.

FIG. 4 is a third side elevation view of the skin hook of FIG. 1.

FIG. 5 is a fourth side elevation view of the skin hook of FIG. 1.

FIG. 6 is a top view of the skin hook of FIG. 1; and,

(Continued)

FIG. 7 is a rear view of the skin hook of FIG. 1. The broken lines shown in FIGS. 1-5 and FIG. 7 illustrate portions of the skin hook that form no part of the claimed design.

1 Claim, 4 Drawing Sheets
